DESIGN FOR A FREEZER CABINET

Wilford H. Teeter, Dayton, Ohio, assignor to
General Motors Corporation, Dayton, Ohio, a
corporation of Delaware

Application May 27, 1943, Serial No. 110,307

Term of patent 14 years

To all whom it may concern:

Be it known that I, Wilford H. Teeter, a citizen of the United States, residing at the city of Dayton, in the county of Montgomery and State of Ohio, have invented a new, original, and ornamental Design for a Freezer Cabinet, of which the following is a specification, reference being had to the accompanying drawing, forming part thereof.

In the drawing:

Fig. 1 is a front elevational view of the freezer cabinet, showing my new design;

Fig. 2 is an end elevational view;

Fig. 3 is a top plan view; and

Fig. 4 is a front perspective view thereof, on a reduced scale.

I claim:

The ornamental design for a freezer cabinet, as shown.
